(57) **CLAIM**

The ornamental design for a handle grip for a drill, as shown and described.

DESCRIPTION

FIG. 1 is a right side elevational view of a handle grip for a drill showing my new design.

FIG. 2 is a left side elevational view thereof.

FIG. 3 is a front elevational view thereof; and,

FIG. 4 is a rear elevational view thereof.

The broken lines are for illustrative purposes only and form no part of the invention.
